UNITED STATES PATENT OFFICE

GEORGE MANOS, OF NEW YORK, N. Y., ASSIGNOR OF ONE-HALF TO ANTHONY C. FLOROS,
OF NEW YORK, N. Y.

DESIGN FOR A SPELLING GAME-BOARD

Application filed November 1, 1932. Serial No. 45,693. Term of patent 3½ years.

To all whom it may concern:

Be it known that I, GEORGE MANOS, a citizen of Greece, residing at New York city, in the county of New York and State of New York, have invented a new, original, and ornamental Design for a Spelling Game-Board, of which the following is a specification, reference being had to the accompanying drawing, forming part thereof.

Fig. 1 is a face view of a spelling game-board showing my new design.

Fig. 2 is a side view of the same.

I claim:

The ornamental design for a spelling game-board, as shown.

In testimony whereof I have affixed my signature this 26th day of October, 1932.

GEORGE MANOS.
